CLAIM

The ornamental design for a luggage with multiple grip handles, as shown and described.

DESCRIPTION

FIG. 1 is a front perspective view of a luggage with multiple grip handles formed along a vertical direction of the luggage;

FIG. 2 is a front elevational view thereof;

FIG. 3 is a first side elevational view thereof;

FIG. 4 is a second side elevational view thereof;

FIG. 5 is a top elevational view thereof;

FIG. 6 is a rear elevational view thereof;

FIG. 7 is a side perspective view thereof;

FIG. 8 is a bottom elevation view thereof;

FIG. 9 is a front perspective view of a luggage with multiple grip handles formed along an horizontal direction of the luggage;

FIG. 10 is a front elevational view thereof;

FIG. 11 is a first side elevational view thereof;

FIG. 12 is a second side elevational view thereof;

FIG. 13 is a top elevational view thereof;

FIG. 14 is a rear elevational view thereof;

FIG. 15 is a side perspective view thereof; and,

FIG. 16 is a bottom elevation view thereof.

The broken lines illustrate portions of the luggage with multiple grip handles and form no part of the claimed design.
